Edwin Leslie Lorden, Los Angeles, Calif., assignor to William Nathanson, Los Angeles, Calif.

Application May 11, 1938, Serial No. 77,129

Term of patent 3½ years

To all whom it may concern:

Be it known that I, Edwin Leslie Lorden, a citizen of the United States, residing at Los Angeles, in the county of Los Angeles and State of California, have invented a new, original, and ornamental Design for a Radio or Phonograph Cabinet Grille or Similar Article, of which the following is a specification, reference being had to the accompanying drawing, forming part thereof.

Fig. 1 is a front elevational view of a radio or

phonograph cabinet grille showing my new design.

Fig. 2 is a horizontal section taken on the line 2—2 of Fig. 1.

Fig. 3 is a side elevational view of the radio or phonograph cabinet grille.

I claim:

The ornamental design for a radio or phonograph cabinet grille or similar article, as shown.

EDWIN LESLIE LORDEN.
